ABSTRACT: A slide-fastener stringer having a pair of coupling elements mounted, for intermeshing upon movement of a slider therealong, upon juxtaposed edges of respective support tapes. The support tapes are each provided with a longitudinal row of openings for cooperation with the needle mechanism of an apparatus designed to attach the stringer to a garment or other fabric. The openings are formed by pushing back at least one warp thread extending parallel to the coupling element by thrusting a wedge-shaped needle or lance into the weave. A plurality of such lances may be provided in transversely staggered longitudinally spaced relation to force back the warp thread in successive stages.

METHOD OF MAKING A SLIDE-FASTENER STRINGER

My present invention relates to slide fasteners of the type in which a coupling element is provided upon each of the mutually confronting edges of a pair of support or carrier tapes or bands for intermeshing upon movement of a slider along the coupling elements in one direction and for disengagement upon movement of the slider in the opposite direction; more particularly, the invention is directed to an arrangement for facilitating the application of a separable slide fastener of this type to a garment or other sheetlike member upon which the closure is to be mounted, and to a method of making the improved slide fastener and an apparatus for carrying out this method.

In my copending applications Ser. No. 562,877, filed July 5, 1966, now U.S. Pat. No. 3,488,239 granted Jan. 6, 1970, and Ser. No. 675,697, filed Oct. 16, 1967, now U.S. Pat. No. 3,456,306 granted July 22, 1969 and my prior applications mentioned therein, there are described slide-fastener closures of the type in which continuous coupling elements are provided upon each of the confronting edges of a pair of parallel support tapes or bands, the coupling elements being helically coiled or undulating monofilamentary thermoplastic members in which each turn forms a coupling head receivable between the turns of the opposed coupling element.

The coupling elements are generally stitched to the support tapes or are held in place therein by passing the coupling heads of each element through a respective opening formed between the threads of the fabric (knitted or woven) tape so that the threads of the latter tightly hug the shanks of each coupling head and may be shrunk therearound to anchor the coupling elements in place. In the most common practice, a core or fillet or bead of flexible material extends within or along the coupling element and the latter is held in place by stitching the turns of the coupling element and its fillet, core or bead in place by a single or double chain stitch which also has the function of accurately positioning the shanks and thereby separating the coupling heads. The present invention is primarily concerned with slide-fastener stringers or stringer halves of this general type.

It has been proposed, in connection with separable slide fasteners having woven or knitted fabric support tapes to form a longitudinal row of openings alongside the coupling elements, i.e. parallel thereto, with a relatively uniform spacing such that the openings may cooperate with members of a stitching machine, e.g. the stitching needles, designed to mount each slide-fastener half upon a respective piece of underlying material, e.g. an edge of a garment or some other fabric article. It has been the general practice heretofore to form these openings by weaving them or knitting them in situ or by stamping them from a generally continuous support tape. Such operations have the important disadvantage that the formation of the openings during the manufacture of the support tape may lead to inaccuracy in the spacing of the openings, requires expensive machinery and highly skilled operating personnel, and cannot be readily accommodated to changes in the spacing or the location of these openings. Similarly, stamping techniques may create inaccuracy, but have the more significant disadvantage that they greatly weaken the support tape at precisely the region in which greatest strength is required to take up the stresses applied to the closure, i.e. the location immediately adjoining the coupling elements.

It is, therefore, the principal object of the present invention to provide an improved slide-fastener stringer, or stringer half, having a longitudinal array of uniformly spaced openings parallel to the coupling element and free from the disadvantages of earlier systems, i.e. high cost, limited accuracy, and a tendency to weaken the region between the point at which the coupling element is affixed to the support tape and the location at which the tape is secured to the substrate or fabric article.

Another object of my invention is the provision of an improved method of making a slide-fastener stringer, or stringer half, in which the disadvantages of earlier methods are

avoided and the aforescribed row of longitudinally spaced openings can be formed with a minimum of difficulty, in a conveniently regulatable manner with respect to the size and location of the openings and at relatively low cost.

- 5 Still another object of my instant invention is the provision of an improved apparatus for forming a longitudinal array of openings in a slide-fastener stringer or stringer half, which obviates the need for the storage of quantities of tape with different numbers of rows of such openings, with a variety of interopening spacings, and with various positional differences of the array of openings.

These objects and others which will become apparent hereinafter are attained, in accordance with the present invention, by a system for forming a longitudinal array of openings in a support tape of a slide-fastener closure whereby one or more warp threads, extending parallel to the edge of the support tape at which the coupling element is or is to be situated, are thrust laterally, preferably away from this edge and/or the coupling element, through a distance of about 1 mm. or more, to form the row of openings without piercing or rupturing the displaced thread.

According to a more specific feature of this invention, the warp thread of the woven fabric tape is pushed to the side in a succession of stages by the repeated and periodic insertion into the fabric of wedge-shaped needles staggered progressively outwardly and one behind the latter in the longitudinal direction, the support tape being advanced with respect to these needles. The thread-displacement needles may be mounted upon the vertically reciprocable shank of a sewing machine whose pressure foot bears upon the fabric tape in the region in which the needles are thrust through this tape.

The slide-fastener stringer, according to the present invention, thus comprises two support tapes having mutually confronting longitudinal edges upon which are fastened respective continuous coupling elements of the aforescribed type, the coupling elements being interengageable in the usual manner upon movement of a slider of conventional construction therealong.

40 Each of the support tapes is formed with one or more rows of openings and intervening strands of the fabric of the type to accommodate cooperating formations, members or needles of the stitching machine whereby the tape is mounted upon a fabric or other member to be provided with the slide-fastener closure.

45 The stringer, preferably with its coupling elements in an interlocked condition, is advanced continuously or periodically past the opening-forming location at which respective arrays of wedge-shaped needles, flanking the coupling elements on each side thereof, are thrust momentarily through the support tapes with the aid of a sewing machine drive to wedge respective warp threads laterally outwardly through approximately the distance between each pair of adjoining warp threads. The 50 warp-thread-free zones constitute formations at which the support bands are tied to the garment and cooperate with the needles of the binding-off machine, i.e. enabling the support tape to be placed upon the needles of the latter machine. As noted earlier, these longitudinal arrays of openings or warp-free zones lie directly adjacent each respective coupling elements, each wedging needle having along the side facing the coupling element, a flank extending perpendicular to the support tape while its flank facing away from the coupling element diverges outwardly from the vertical or perpendicular flank.

55 Such an arrangement has numerous significant advantages. Thus, the article to which the tape is to be secured, is no longer covered directly adjacent coupling elements and attachment of the tape to the article is facilitated. Of even 60 greater significance is the fact that the row along which the warp thread has been pushed aside, permits the tape to be applied to the bank of a binding-off machine of the type heretofore used for interlacing the article and the support tape with greater ease. Such machines generally have an array of needles adapted to extend through the openings provided in the

support tape. The array of openings provided by lateral shifting of a warp thread, in accordance with the present invention, enables the tape to be mounted on this array of needles with great facility. Surprisingly, the shift of the warp thread in accordance with the present invention has been found to be advantageous also in that the warp thread tends to remain in its shifted position and the band or tape can be displaced, stored or otherwise handled without any danger that the openings thus provided will close by a return of the warp thread to its original position. Of special significance is the fact that the formation of the openings or the needle-accommodating row, according to the present invention, can be effected with ease, without weakening of the fabric tape, can be formed close to the coupling elements and, as a practical matter, can have any desirable width, e.g. from one to several millimeters. The asymmetrical lances or needles, which serve to displace the warp thread, can be conveniently mounted on a sewing machine ram, can be provided in any desirable number and with any desirable spacing, and can have rounded ends of a width such that they do not pierce the threads. Advantageously, they are spaced apart in the direction of advance of the band by approximately the spacing of the weft threads and, as viewed in the direction of movement of the band, laterally overlap.

The above and other objects, features and advantages of the present invention will become more readily apparent from the following description, reference being made to the accompanying drawing in which:

FIG. 1 is a perspective view of a slide-fastener stringer embodying the present invention;

FIG. 1A is a detail view drawn to an enlarged scale of a region of FIG. 1;

FIG. 1B is a view similar to FIG. 1A of another stringer portion mounted upon an article;

FIG. 2 is an end view of the apparatus for shifting the warp thread in accordance with the present invention, the stringer being shown in cross section in a plane perpendicular to its longitudinal direction;

FIG. 3 is a side view of the apparatus of FIG. 2; and

FIG. 4 is a diagrammatic illustration showing how the wedge-shaped needles or lances of the present invention displace the warp thread.

In FIGS. 1 and 1A, I have shown a slide-fastener stringer, the slider of which may be of any conventional type and which may be provided with end-stop members as described in the aforementioned copending applications and which comprises a pair of woven support tapes 1 and 2, whose confronting edges 1a and 2a, are formed with respective coupling elements 3, 4 whose heads are interfitted as shown in FIG. 1 and which are anchored to the support tapes by rows 3a (FIG. 1) and 4a of chain stitches which are looped over the shanks (e.g. 4b of FIG. 1A) and which extend through respective fillets 3c and 4c received within the helical coupling elements. The coupling elements are here shown as flattened helices of a nylon-type monofilamentary synthetic resin (see the aforementioned applications) and can be any conventional continuous coupling elements, e.g. coupling elements of the undulated type as well.

Along the coupling elements 3, 4 and flanking them but close to the bights 4d, there are provided longitudinally extending rows of coupling formations 5 enabling the respective support tapes to be bound into a fabric after being placed upon the needles of the bind-off machine, in the usual manner. A woven fabric substrate is shown at F in FIG. 1B and has thread loops L extending around the stretches 7a of weft threads in the respective arrays to secure the tape 2 to the article F.

As is illustrated in detail in FIG. 1A, the fabric tape 2 is composed of a set of transversely extending, equispaced weft threads 7 interwoven with the warp threads 6 which extend parallel to the coupling elements and orthogonally to the weft 7. A warp thread 6a is shifted from its normal position to the right (FIG. 1A) to form the array 5 of the needle-receiving openings 5a spaced apart by the strips 7a of the weft 7. The

warp thread 6a bears against the adjacent thread 6b which, in turn, has been shifted slightly to the right toward the thread 6c. A thread 6d, unmoved in the process of shifting thread 6a, defines the left-hand boundary of the array 5. From FIG. 1B it can be seen that two arrays 5 and 5' are provided in the fabric band 2' carrying the coupling element 4' which is held in place by the chain stitch 4a' through the core 4c'. The loops L and L' bind the tape 2' to the underlying fabric F.

The warp-free zones 5 and 5' thus constitute arrays of openings 5a which can be thrust onto the needles of a bind-off machine. The thread 6a may be shifted away from the coupling element 4 to a distance d of, say, 1 to 4 mm.

In FIGS. 2-4, I show the apparatus for forming the warp-free zones 5 of FIGS. 1, 1A and 1B. The apparatus comprises a sewing machine ram or spindle 15 which is vertically reciprocable by the sewing machine drive represented at 16 and as indicated by the arrow 17a.

The band 1, 2, is held down by a pressure foot 17 while the band is advanced to the left past the lance location as represented by the arrow 18 via a feed device shown in FIG. 3. The feed device comprises a weighted sprocket wheel 19 engageable with the turns of the coupling elements 3, 4 and rotated periodically in the clockwise sense (arrow 20) by a reciprocating pawl 21 whose motion is represented by the arrow 22 and which is coupled with the sewing-machine drive 16.

As shown in FIG. 3, three longitudinally offset needles 10, 9, 8 serve to displace the thread 6a through the desired dimension, exaggerated in FIG. 2 and represented by the dimension D, the needles 8, 9, 10 overlapping successively when viewed from the end (FIG. 2). The needles are transversely staggered (FIG. 2) and are of lance configuration with slightly rounded points receivable between each pair of adjacent warp and each pair of adjacent weft threads.

The lances each have a straight flank 23 extending vertically (FIG. 2) and perpendicular to the plane of the fabric (FIG. 4) as well as a flank 12 inclined to this perpendicular flank inwardly with respect to the coupling element in the direction in which the lance is thrust through the fabric. The width w of the rounded tip 11 of each lance is less than the normal center-to-center spacing S of the warp thread 6a while the base of the wedge has a width W exceeding the interthread spacing and designed to push the thread 6a to the right (FIG. 4). Upon withdrawal of the shank k of lances 8-10, the stringer is advanced to the left for a successive operation in which the lances engage the thread 6a and push it further to the right (FIG. 4).

I claim:

1. In a method of making a slide-fastener assembly in which a pair of woven-fabric support tapes have juxtaposed edges each provided with a longitudinally extending coupling element engageable with the coupling element of the other tape and with longitudinally extending warp threads interwoven with transversely extending weft threads and the support tapes are interlaced with fabric on a binding-off machine having an array of needles, the improvement which comprises the steps of:

a. advancing said support tapes along a transport path in increments corresponding to the spacing between the weft threads; and
b. thrusting a wedge member having a row of wedge elements between the adjacent weft threads to displace at least one of the warp threads out of its original position to form openings accommodating said needles upon each increment of displacement of said tapes, said wedge elements of said row being offset in the longitudinal direction and having wedging surfaces successively spaced at greater distances from the coupling element and thrust simultaneously between the respective pairs of weft threads to shift said warp thread in a plurality of stages.

2. The method defined in claim 1 wherein said warp thread is the warp thread immediately adjacent the coupling element.

3. The method defined in claim 1 wherein said wedge elements each have a flank parallel to the direction in which the wedge elements are thrust through said tapes and a wedge surface inclined thereto and converging in the thrust direction.
